UNITED STATES PATENT OFFICE.

ANDREW DEVAN, OF MISSOULA, MONTANA.

CATTLE-GUARD.

No. 810,328.

Specification of Letters Patent.

Patented Jan. 16, 1906.

Application filed May 29, 1905. Serial No. 262,843.

To all whom it may concern:

Be it known that I, ANDREW DEVAN, a citizen of the United States, residing at Missoula, in the county of Missoula and State of Montana, have invented new and useful Improvements in Cattle-Guards, of which the following is a specification.

This invention relates to surface cattle-guards for railroads; and the object thereof is to provide a cattle-guard which shall effectively prevent the access of cattle from grade-crossings to the adjacent right of way.

The invention further aims to provide a cattle-guard presenting the advantage of comparatively slight cost, capable of ready attachment and of removability in sections for renewal in event of damage when desired, and freedom from interference with repairs of track other than the removal of the tie or ties to which the cattle-guard section or sections are attached.

The invention further aims to provide a cattle-guard with a serrated or toothed edge so arranged that the animal is free to pull his foot or leg out of the guard without being pricked by the teeth thereof; but if the animal goes to move forward with the other foot he presses the hindered foot or leg or fore part of his leg against the teeth of the guard, pricking without tearing the flesh, and consequently compelling the animal to back away and extricate himself.

With the foregoing and other objects in view the invention consists of the novel construction, combination, and arrangement of parts hereinafter more specifically referred to, illustrated in the accompanying drawings, and particularly pointed out in the claims hereunto appended.

In describing the invention in detail reference is had to the accompanying drawings, which form a part of this specification, wherein like reference characters denote corresponding parts throughout the several views, and in which—

Figure 1 is a top plan view of a cattle-guard constructed in accordance with this invention and as applied to a railway-track. Fig. 2 is a longitudinal sectional view thereof. Fig. 3 is a perspective view of a modified form of cattle-guard.

In the practice of my invention I connect to a number of the cross-ties 1 of a railroad-track, as, say, five, more or less, on one or both sides of a cross-road, station-grounds, or other place open to the inclosed right of way of a rail-

road, a sectional sheet-metal cattle-guard, one or two sections of which are secured to each of the ties between the rails 2 and two sections to each tie, one on the outer side of each of the rails.

Cattle-guards as shown in Figs. 1 and 2 are each formed of a single sheet of metal and so constructed as to provide a front and a rear member 3 4, respectively, and a bottom portion 5. The members 3 and 4 merge at the bottom into a portion 5. The members 3 4 extend at an inclination, and said member 3 is of greater length than said member 4, and each of the said members 3 4 has its upper edge serrated or provided with teeth, as at 6. The arranging of the members 3 4 at an inclination forms a pocket 7, into which the animal's foot or leg is compelled to enter if the animal should attempt to gain access to the right of way. The inclination of the members 3 4 is in what is termed a "forward" direction, or, in other words, toward the tie to which a cattle-guard is secured. The cattle-guard consists of three or more sections, preferably three sections—an intermediate section and two outer sections. The intermediate section is arranged between the track-rails, and the outer sections are arranged exterior of the track-rails. If desirable, the intermediate section may be divided into two members. This facilitates shipment, and the two members which form the intermediate section may be suitably secured together or secured in such a manner that a small space will be arranged between them. It is thought unnecessary to show this division of the intermediate section. The end sections of the cattle-guard preferably are of much less width than the intermediate section, yet they are of the same contour. The front member 3 of the cattle-guard is what is termed the "stationary" member, while the rear member 4 is what is termed a "spring" member, as the front member 3 is secured to the tie, while the rear member 4 is free. Consequently if an animal walks thereon it will give and cause the foot or leg of the animal to fall into the pocket 7, the character of the material of the cattle-guard being such that after the rear member 4 has been pressed downwardly and pressure is removed therefrom it will resume its normal position.

As before stated, the cattle-guard has its front member 3 secured to the tie 1, any suitable holdfast devices for this purpose being employed, the reference character 8 denoting the holdfast devices

which extend through the member 3 and engage in the tie. To support the front member 3, as well as to assist in retaining the same at its proper inclination, the tie is cut away, as at 9, forming inclined bearing-surfaces, one between the rails and one exterior of the rails. That portion of the tie which supports the rails is not cut away. So, consequently, the necessary bearing for the rails is still had, although the tie is provided with bearing-surfaces for the front member 3 of the cattle-guard. That portion of the member 3 which projects from the top edge of the bearing-surfaces 9 is bent at a slightly-greater angle than the remaining portion of the member 3.

In the modified form shown in Fig. 3 the cattle-guard is formed of two separate members 10 11, the member 10 being the front member and the member 11 the rear member. The member 10 is of much greater length than the member 11. The top edge of the member 10 is serrated or provided with teeth, as at 12, and the said member 10 projects forwardly at an inclination and is secured to the tie 1 in the same manner as the member 3 heretofore referred to, the tie being provided with the inclined bearing-surfaces 9. The member 11 is of less length than the member 10 and is secured to said member 10, near the lower end thereof, and extends forwardly at an inclination at an angle not as great as the angle of the member 10, thereby forming a pocket 13, which receives the foot or leg of the animal. The upper edge of the member 11 is serrated or toothed, as at 14.

When the cattle-guard according to Fig. 1 is set up, the bottom portion 5 rests upon the track-bed and abuts against one tie, and the member 4 projects away from the tie against which the bottom 5 abuts, while the member 3 extends forwardly at an inclination and is secured to the adjacent tie in a manner as hereinbefore set forth.

It will be evident from the foregoing constructions that if an animal should place his foot or leg in one of the pockets he would be free to pull it out without being pricked by the teeth; but if the animal goes to move forward with the other foot he presses the hindered foot or fore part of his leg against the teeth of the guard—that is to say, the rear member—which would prick the leg without tearing the flesh, and consequently compel the animal to back away and extricate himself.

Although a series of cattle-guards is shown extending in one direction, yet certain of them can extend in an opposite direction, so that it would prevent the cattle or horses from coming out over the guard where they might happen to get on the right of way through broken fences. It is thought unnecessary to show the extending of the cattle-guards in different directions. The serrated

or toothed edges of the cattle-guards are intended to face the animal as it approaches—that is to say, the toothed edge will be toward the road or highway; but should the animal happen to step upon the rear section 70 it is evident, owing to the fact that it is constructed so as to give, that it would cause the animal's foot to slide into the pocket formed by the two members. Although the cattle-guard is shown formed of flat sheet metal, 75 yet, if desired, the metal can be corrugated.

Having thus fully described my invention, what I claim as new, and desire to secure by Letters Patent, is—

1. A cattle-guard consisting of a pair of 80 members extending in the same direction and forming a pocket, said members being arranged between a pair of rail-ties, and said members further having the upper edges thereof serrated.

2. A cattle-guard consisting of a front and a rear member extending at an inclination and suitably connected together, thereby forming a pocket, said members adapted to be interposed between a pair of rail-ties and 90 each of said members having its upper edge serrated.

3. A cattle-guard comprising a front and a rear member extending at an inclination, one of said members secured to a tie and the other 95 of said members being resilient, said members suitably connected together at their lower ends to form a pocket.

4. A cattle-guard comprising a front and rear member extending at an inclination, one 100 of said members secured to a tie and the other of said members being resilient, said members suitably connected together at their lower ends to form a pocket, and each of said members having its upper edge serrated. 105

5. A cattle-guard adapted to be interposed between a pair of ties and comprising a fixed and a resilient inclined member, said movable member projecting away from one of the ties and the other of said members fixed to 110 the other of said ties.

6. A cattle-guard adapted to be interposed between a pair of ties and comprising a fixed and a resilient member suitably connected together at their lower ends and spaced 115 apart to form a pocket, one of said members fixed to one of said ties, said members having a serrated edge.

7. The combination with a railway-tie having an inclined bearing-surface, of a cattle-guard comprising a front and a rear member extending at an inclination and having serrated edges, said members suitably spaced apart to form a pocket, and one of said members resting upon said bearing-surface and 125 fixed to said tie.

8. The combination with a railway-tie having an inclined bearing-surface, of a cattle-guard comprising a front and a rear member extending at an inclination and having ser- 130

rated edges, said members suitably spaced apart to form a pocket, and one of said members resting upon said bearing-surface and fixed to said tie, said fixed member having a portion thereof extending at a greater inclination than the remaining portion thereof.

9. A cattle-guard consisting of a piece of sheet-metal material bent to form a front and rear inclined member terminating at their lower ends in a body portion adapted to rest upon the track-bed, one of said members being of less length than the other of said members and both of said members having their top edges serrated, said members being suitably spaced apart to form a pocket.

10. A cattle-guard consisting of a piece of sheet-metal material bent to form front and rear inclined members terminating at their lower ends in a body portion adapted to rest upon the track-bed, one of said members being of less length than the other of said members and both of said members having their top edges serrated, said members being suitably spaced apart to form a pocket, combined with a railway-tie having an inclined bearing-

surface for said longer member, and means for securing said elongated member to the said tie.

11. A cattle-guard comprising a plurality of sections and each consisting of a piece of sheet-metal material bent to form front and rear inclined members terminating at their lower ends in a body portion adapted to rest upon the track-bed, one of said members being of less length than the other of said members and both of said members having their top edges serrated, said members being suitably spaced apart to form a pocket, combined with a railway-tie having an inclined bearing-surface for said longer member, and means for securing said elongated member to the said tie.

In testimony whereof I have hereunto set my hand in presence of two subscribing witnesses.
